UNITED STATES PATENT OFFICE.

WILLIAM G. KENDALL, OF NEWARK, NEW JERSEY.

COMPACT EJECTOR FOR VANITY CASES.

Application filed July 14, 1926. Serial No. 122,404.

This invention relates to compact ejectors for vanity cases and has for an object to provide an improved construction which may be operated by the same button that unlatches the case.

Another object of the invention is to provide an ejector wherein the structure bows upwardly and thereby positively forces the compact out of the holder.

A further object is to provide a compact ejector for vanity cases wherein a sliding ejector structure is provided and so associated with the catch that upon an exaggerated operation of the catch the ejector will be caused to function.

In the accompanying drawing—

Figure 1 is a top plan view of a vanity case with the lid shown open and certain parts broken away for illustrating an embodiment of the invention associated with the case.

Figure 2 is an enlarged sectional view through the case shown in Figure 1, the same being taken on line 2—2 of Figure 1.

Figure 3 is a sectional view through Figure 2 on line 3—3.

Figure 4 is a perspective view of an ejector strip disclosing certain features of the invention.

Referring to the accompanying drawing by numerals, 1 indicates the body of a vanity case and 2 a cover or lid hinged thereto. The detail construction of the vanity case forms no part of the present invention except in its association with the ejector hereinafter fully described. However, it will

be noted that the lid 2 is provided with a pressed out portion 3 for receiving the hook 4 forming part of the catch 5. The catch 5 is provided with a button 6 extending through a suitable aperture 7 in body 1 and is also provided with spring sections 8 and 9. The spring sections 8 and 9 press against the annular compact holder 10 which is provided with pressed out resilient portions 11 for resiliently holding the compact plate 12 in place. The members 11 act as holders so that the compact plate cannot accidentally fall out, though these members will yield

when pressure is exerted on the plate to move the same toward the lid 2. Adjacent the button 6 the holder 10 is provided with an opening 13 through which the ejecting strip 14 extends. This strip is of resilient metal and is provided with a looped portion 15 at one end and a series of cor-

rugations 16 at the opposite end. A small rod or resilient wire 17 extends through the loop 15 so as to prevent any accidental displacement of the strip 14. The corrugations 16 stiffen the strip 14 at the end and also guide the same through the opening 18 in holder 10. A ring 19 supports the strip 14 as shown in Figure 2 and permits the same to freely slide back and forth.

It will be noted that when the strip is in operative position, the end 20 will be bearing against the side wall 21 of body 1 so that when the front section 5' of catch 5 presses against the loop 15, strip 14 will be bowed upwardly centrally. The parts are so proportioned that strip 14 will be bowed upwardly sufficiently to raise the compact plate 12 out of engagement with the resilient holders.

From the construction set forth, it will be observed that when button 6 is pressed somewhat, the catch hook 4 will be disengaged for permitting lid 2 to be swung to an open position. If the button 6 is pressed inwardly as far as possible, not only will the lid 2 be released but the strip 14 will be bowed sufficiently to eject the compact plate 12 whereby a new one may be provided. As soon as the button 6 has been released it will move back to its original position and also the resilient strip 14 will move back to its original position. This will allow a new compact to be snapped beneath the members 11 without adjusting any of the parts.

What I claim is:

1. In a compact ejector for vanity cases provided with a compact holder arranged in the case and positioned to receive and normally retain the compact, a resilient ejector strip slidably mounted in the lower part of said holder and beneath said compact with one end near part of said casing, and manually actuated means acting on the other end for moving said strip longitudinally and thereby bowing said strip whereby the same will force said compact out of engagement with said holder.

2. In a compact ejector for vanity cases provided with a body, a lid, and a catch, a strip extending from near one side to the opposite side of a said body, said strip being adapted to be positioned beneath a compact arranged in said body, and means forming part of the catch for pressing against one end of said strip for forcing the other end

against said body and thereby bowing the strip substantially centrally for ejecting the compact arranged in said body.

3. In a vanity case adapted to be provided with a compact, a compact ejector including a flexible metallic strip positioned beneath said compact, said strip being formed with corrugations at one end for stiffening and guiding the strip, means forming part of the case for engaging and guiding the corrugated part of the strip, and means extending from the catch of the case for engaging said strip at one end whereby said strip may be pushed and bowed substantially centrally for ejecting said compact.

4. A vanity case adapted to receive a compact including a body, a lid hinged to said body, a catch for said lid having a button and spring members, an ejecting strip arranged beneath said compact and with one end in the path of movement of said spring

members, and the other end adjacent the body at the diametrically opposite side, and means for guiding said strip when moved longitudinally whereby when said body and spring members are pressed inwardly a predetermined distance, said strip will be pressed against the said body and bowed sufficiently for ejecting said compact.

5. In a vanity case provided with a thumb operated catch and a compact holding ring structure adapted to receive and normally retain a compact, an ejector slidably mounted in said ring structure and positioned beneath said compact, said ejector including a strip of resilient metal having a stiffened end adapted to engage the body of the case, and a looped end adapted to be engaged by said catch whereby when said catch is pressed inwardly an extreme distance the spring will be bowed for ejecting said compact.

WILLIAM G. KENDALL.
